UNITED STATES PATENT OFFICE.

CLARENCE H. HOWARD AND HARRY M. PFLAGER, OF ST. LOUIS, MISSOURI.

RAILROAD-CAR.

No. 835,527.

Specification of Letters Patent.

Patented Nov. 13, 1906.

Application filed June 9, 1906. Serial No. 320,988.

To all whom it may concern:

Be it known that we, CLARENCE H. HOWARD and HARRY M. PFLAGER, citizens of the United States, residing at St. Louis, in the 5 State of Missouri, have invented a new and useful Improvement in Railroad - Cars, of which the following is a specification.

Our invention relates to an improvement in the construction of a railroad passenger-car in which the end platforms and vestibules are dispensed with and the entrance-opening thereto formed through the side or sides midway, or thereabout, between the car-trucks, and has for its object to increase the seating 15 capacity of the car and facilitate the entrance and exit of the passengers to and from the same.

The invention consists in means for supporting and receiving the thrust of the divided portions of the side sills and other longitudinal members of the car-frame which are cut away or omitted at the said opening through the side of the car, for enabling the car-step hangers and steps to be fixed thereat 25 within the plane of the car side, combined with other features of novelty as hereinafter described and claimed, reference being had to the accompanying drawings, forming part of this specification, whereon—

30 Figure 1 is a side elevation of a portion of a railroad passenger-car having its entrance-opening through the side intermediate to the car-trucks and otherwise constructed according to our invention; Fig. 2, a vertical trans- 35 verse section to enlarged scale through the wood plate and underframe of the car-body and combined parts of our invention at one side of the longitudinal center of the car, on line 2 2 in Fig. 1; Fig. 3, a similar view to Fig. 2, omitting the upright metallic side-frame seen therein around the entrance-opening and forming part of our invention; Fig. 4, a vertical transverse section to enlarged scale through the said frame and through the 45 side sill and belt-rail of the car-body, on line 4 4 in Fig. 1; Fig. 5, a top plan view of the metallic sill-plate (seen in Figs. 1, 2, 3, and 4) fixed to the underframe of the car and forming part of our invention; Fig. 6, a longitudinal sectional side elevation thereof, on line 50 6 6 in Fig. 5; and Fig. 7, a cross-sectional end elevation of the same on line 7 7 in Fig. 5.

Like letters and numerals of reference denote like parts in all the figures.

55 In carrying out our invention we eliminate the present platform and vestibule-entrance

at each end of the car, and in lieu thereof form through one or each side of the car-body *a* intermediate to the car-trucks (not shown) an opening *b*, which forms the entrance to the car and is adapted to be opened and closed by two doors 1, hinged either to the sides 2, respectively, of an upright metallic frame *c*, surrounding the entrance-opening *b* and secured to the side of the car-body, 60 as hereinafter more particularly described, or, when the frame *c* is omitted, to the upright posts 3 (indicated by dotted lines in Figs. 1 and 3) or other suitable part of the woodwork adjacent to the opening *b*, the 65 doors 1 preferably meeting when closed at the middle of the opening *b*, as shown.

For forming the opening *b* through the side of the car-body *a* we preferably cut away or omit a portion of the side sill 4 and adjacent 70 belt-rail 5 and other longitudinal side members thereat (if any) corresponding in length or thereabout to the width of the opening *b*, in which case (assuming that an entrance-opening *b* is formed through each side of the 75 car-body and opposite to each other) the divided portions of the side sills 4 are supported by a metallic base-plate *d*, (hereinafter termed "sill-plate,") which is preferably composed of cast-steel integral throughout 80 and in the present case extends entirely across the car-body, the sill-plate *d* being fixed to the divided portions of the side sills 4 and to the intermediate and middle longitudinal sills 6 and 6', respectively, preferably 85 on their under side, by bolts or otherwise, (not shown,) which pass through the holes 7 therefor in the sill-plate *d*, Fig. 5, and through the sills 4, 6, and 6'. In each side edge of the sill-plate *d*, preferably midway between 90 its ends, is formed a rectangular-shaped recess 8, which coincides with the entrance-opening *b* and extends therefrom inwardly toward the intermediate sill 6 or middle of the car-body, the recess 8 registering with a 95 similar recessed opening 8', formed above the sill-plate *d* through the car-floor *e*. On the sill-plate *d* at or adjacent to the lateral and inner edges of each recess 8 are formed upright flanges or webs 9 and 10, respectively, 100 the inner flange 9 bearing, preferably, against the outer upright face of the intermediate sill 6, to which it is fixed by bolts (or rivets) 11, and the lateral flanges 10 against the ends, 105 respectively, of the separated portions of the side sill 4. The sill-plate *d* is preferably strengthened at each end and intermediate 110

thereto by transverse depending ribs 12 12', the ribs 12' being preferably flush with the lateral edges of the recesses 8. Furthermore, on the sill-plate *d* are formed upright longitudinal flanges 13, which unite with the lateral flanges 10 of the recesses 8 at right angles thereto and bear against the inside upright faces of the end portions, respectively, of the side sills 4, to which they are fixed by 10 bolts (or rivets) 14, as shown. By this construction it will be noted that the divided end portions of each side sill 4 are practically held in housings therefor formed by the sill-plate *d*, combined with the flanges 10 and 13, the 15 ends of the said portions abutting against the flanges 10, whereby the thrust or compressive force of each separated portion of the side sills 4 is transmitted to the sill-plate *d* and balanced by the opposing force of the 20 corresponding opposing portions of the side sills 4; also, that by cutting away the side sill 4 and forming the recesses 8 and 8' in the sill-plate *d* and car-floor *e* immediately behind each entrance-opening *b* we are enabled to 25 fix the step-hangers 15, with the steps and risers 16 and 16', to the sides or flanges 10 of the recesses 8 within the plane of the car side.

From the sill-plate *d* depend the queen-posts *f* for the truss-rod 17 of the car-body *a*, 30 which are arranged and operate in the usual well-known manner, the queen-posts *f* in the present case being shown integral with the sill-plate *d*, or they may be of separate construction and fixed to the sill-plate *d* by bolts 35 or otherwise.

Surrounding each entrance-opening *b* and extending downward therefrom beneath the space occupied by the step-hangers 15 with their appurtenances is preferably arranged, in 40 the present case, the upright rectangular-shaped metallic side frame *c*, before referred to, composed, preferably, of cast-steel integral throughout and having extended side portions 18, which bear against, preferably, 45 the upright faces of the end portions of the divided side sill 4 and corresponding belt-rail 5, the frame *c* where it surrounds the entrance-opening *b* being preferably L-shaped in cross-section, its inwardly-projecting legs 50 19 bearing at the sides of the frame *c* against the ends, respectively, of the separated portions of the belt-rail 5 and against the lateral flanges 10 of the recesses 8 through the sill-plate *d* and at the top against the under side 55 of the wood plate 20, to which it is secured by bolts 21.

Projecting from the lateral extended portions 18 of the frame *c* are horizontal flanges 22, which, preferably, bear against the top 60 side of the end portions, respectively, of the divided side sill 4, to which and to the sill-plate *d* the flanges 22 are fixed by bolts (or rivets) 22', similar flanges 23 projecting from the lateral portions 18 of the frame *c* and 65 preferably bearing against the under side of

the end portions, respectively, of the corresponding divided belt-rail 5, the whole forming a rigid truss to the divided portions of the side sill 4 and to the side frame of the car-body at and adjacent to the entrance-opening *b*. 70

The side frames *c* may be used either in combination with the sill-plate *d*, as described and shown, or without the sill-plate *d*, in which case the inwardly-projecting legs 75 19 of the L-shaped portion of the frame *c*, surrounding the entrance-opening *b*, will bear directly against the ends of the separated portions of the side sill 4, or the sill-plate *d* may be used without the side frames *c* or 80 with one side frame *c* when only one entrance-opening *b* to the car is desired, in which case the sill-plate *d* may extend part way instead of entirely across the car-body. When the sill-plate *d* is used without the side frames *c*, 85 the end portions of the divided side sill 4, belt-rail 5, and other divided longitudinal side members (if any) of the car-frame are united to each other by the upright posts 3, before referred to and indicated by the dotted lines in Figs. 1 and 3, which form the framework of the entrance-opening *b*, or the divided portions of the said members may be otherwise connected together and arranged to form the framework of the opening *b*, as 90 95 found most suitable. Furthermore, the sill-plate *d*, whether used alone or in combination with the side frames *c*, may be made in two parts having meeting flanges 24 (indicated by dotted lines in Figs. 5 and 7) and 100 secured together therethrough by bolts or rivets. (Not shown.)

Each recessed opening 8' through the car-floor *e* is adapted to be closed and opened by two trap-doors 25, which are hinged, respectively, to the floor *e* along the corresponding side of the opening 8' clear of the closed doors 1, as seen in Figs. 1, 2, and 3, the trap-doors 25, when closed together over the openings 8' and 8 forming practically a continuation 110 of the car-floor *e*.

For opening the doors 1 the trap-doors 25 are first thrown upward on their hinges into the upright position, which uncovers the floor-openings 8' 8, when the doors 1 are 115 opened or swung inward against the trap-doors 25 and access thereby obtained to the steps 16 and entrance-opening *b*, the doors 1, with the trap-doors 25, at the same time operating as side screens to the floor-opening 8' 120 and compelling passengers to enter and leave the openings 8 and 8' in a direction facing the entrance-opening *b*, and thereby preventing accident.

We do not limit ourselves to the particular 125 shape of the sill-plate *d* and side frames *c* nor to the means for adapting the same to support and receive the thrust of the divided side sills 4 and other divided longitudinal members of the car-frame described, and 130

shown on the drawings, as the sill-plate *d* and side frames *c* may be otherwise adapted for this purpose as found most suitable in practice without departing from the principle of 5 our invention.

By this invention in dispensing with the ordinary end platforms and substituting therefor an opening through the side of the car near the middle of considerably less width 10 than the space occupied by the platforms the inside free length, and consequently the seating capacity of the car, is increased and the entrance and exit of the passengers to and from the same facilitated by the reduced distance 15 to be traveled, increased aisle-space also being formed when the doors opposite to those in use are closed.

What we claim as our invention, and desire to secure by Letters Patent, is—
20 1. In a railroad passenger-car of the character described, having an entrance-opening through the side intermediate to the car-trucks and having the side sill divided thereat, the combination of a metallic plate fixed 25 to the car-underframe and adapted to support the separated portions of the said sill, and to form abutments to the ends of the said portions, the said plate having a recess therethrough coincident with the entrance- 30 opening and registering with a similar recessed opening in the car-floor, substantially as described and for the purpose set forth.

2. In a railroad passenger-car of the character described, having an entrance-opening 35 through the side intermediate to the car-trucks, and having the side sill divided thereat, the combination of a metallic plate fixed

to the car-underframe and adapted to support the separated portions of the said sill and to form abutments to the ends of the 40 said portions, the said plate having a recess therethrough coincident with the entrance-opening and registering with a similar recessed opening in the car-floor, and means for closing and exposing the said openings 45 respectively, substantially as described and for the purpose set forth.

3. In a railroad passenger-car of the character described, having an entrance-opening through the side intermediate to the car- 50 trucks, and having the side sill divided thereat, the combination of a metallic plate fixed to the car-underframe and adapted to support the separated portions of the said sill and to form abutments to the ends of the 55 said portions, the said plate having a recess therethrough coincident with the entrance-opening and registering with a similar recessed opening through the car-floor, an upright metallic frame surrounding the entrance-opening and extending downward therefrom, the said frame being adapted to bear against the separated portions of the side sill and belt rail, and means for fixing the frame to the said sill and rail, substan- 60 tially as described.

In testimony whereof we have signed our names to this specification in the presence of two subscribing witnesses.

CLARENCE H. HOWARD.
HARRY M. PFLAGER.
